UNITED STATES PATENT OFFICE.

JOHN S. SCHAEFFER, OF BROOKVILLE, PENNSYLVANIA.

CROSS-TIE.

No. 857,907.

Specification of Letters Patent.

Patented June 25, 1907.

Application filed March 4, 1907. Serial No. 360,467.

To all whom it may concern:

Be it known that I, JOHN S. SCHAEFFER, a citizen of the United States of America, residing at Brookville, in the county of Jefferson, and State of Pennsylvania, have invented certain new and useful Improvements in Cross-Ties, of which the following is a specification.

This invention relates to railways and particularly to a cross tie for the tracks of railways.

An object of this invention is to provide a concrete cross tie, the specific material being any suitable concrete in proper proportions to produce a stone-like composition when dried and in connection therewith suitable reinforce strips of wire netting or like material embedded in the said concrete.

It is also the purpose of the inventor to provide a concrete cross tie with suitable cushions and spike engaging members suitably embedded in the concrete at the time the same is molded and I prefer that the said cushions shall consist of a series of blocks of alternate thin layers of wood, paper or other yielding material suitably treated by the application of coal tar, asphalt cement or other approved preservative, the said layers of wood and paper resting on strands of wire netting which extend longitudinally of the cross tie from end to end under the said layers of wood or paper; it is furthermore, an object of this invention to provide a wire netting for the body of the cross tie which is preferably tubular and extending from end to end thereof for the purpose of reinforcing the material of the cross tie.

It is furthermore, an object of this invention to provide a tie having depending portions which are preferably under the points of contact of the rails and tie whereby the said tie is reinforced at these points; the said depending portions further serving as an anchoring means for preventing creeping of the said cross ties owing to the fact that the earth would pack around the shoulders of the depending portions and securely anchor it in place.

As a modification of the device referred to I may utilize practically the same cross tie and reinforce except that the said cross tie may be provided with a cushion comprising a plank or board suitably embedded in the concrete structure flush with the upper surface thereof, the said plank being of such

length as to extend beyond the points of contact of the rails with the cross tie.

As a means for securing the rails in place, I may utilize spikes such as are employed in connection with the first mentioned embodiment of the invention, or I may utilize U-shaped bolts having their ends projecting above the surface of the tie and adapted to receive clamps which engage the flanges of the rail and, if such bolts are utilized, suitable nuts may be applied to the ends thereof for clamping the rail in place or, I may utilize a yoke structure which is similar to the U-shaped bolts heretofore referred to except that the ends would be devoid of threads and the said ends would be bent to overlie the flanges of the rail for the purpose of retaining it in place.

A still further object of this invention is to provide a cross tie which tapers in height or vertical thickness from one end to the other for the purpose of elevating the outside rail when the said cross ties are employed at curves of the track, said construction permitting the base of the cross tie to lie flat or horizontal while the pitch of the outer rail is regulated by the thickness of height of the cross tie.

Finally an object of this invention is to provide a cross tie of the character noted, which will possess advantages in points of simplicity, efficiency and durability proving at the same time comparatively inexpensive to manufacture.

With the foregoing and other objects in view, the invention consists in the details of construction and in the arrangement and combination of parts to be hereinafter more fully set forth and claimed.

In describing the invention in detail, reference will be had to the accompanying drawings forming part of this specification wherein like characters denote corresponding parts in the several views, in which—

Figure 1 is a view in elevation of a cross tie embodying the invention with the rails in section. Fig. 2, is a longitudinal sectional view, showing a method of construction. Fig. 3, is a transverse sectional view on the line 3—3 of Fig. 1. Fig. 4, is a transverse sectional view on the line 4—4 of Fig. 2. Fig. 5, is a view in elevation of a rail clamp. Fig. 6, is a detail view showing another means for fastening the rails in place.

In these drawings, A indicates a cross tie

consisting of a concrete base having a series of layers of wire netting for the purpose of reinforcing it. In producing this cross tie I prefer to employ a mold of the desired configuration to produce beveled edges on the cross tie and the said mold should be provided with holes near the ends fixing the gage required for bolts or bars of iron for holding the rails.

10 In the production of the cross tie, wire netting is spread on the bottom of the mold the full length thereof and the said wire netting is extended up the sides and above the top of the box about six inches (6"). The size of the wire and meshes conform to the strength required. Near the end of the box at points corresponding with the gage required, the cushions for the rail are placed which, in this form comprise thin layers of wood or papier 15 mâché or other yielding material of suitable size. It is my purpose, as I have heretofore stated, to treat the wood or papier mâché with a preservative consisting of coal tar or asphalt cement. The wood and papier 20 mâché blocks B, are placed in position alternately with intermediate layers of the wire netting C, until the cushion formed thereby is from one-third to one-half of the depth of the cross tie although the proportion or size 25 of the cushion with respect to the cross tie may be varied to suit particular requirements. The cushion thus formed of alternate layers of wood or other elastic material and the wire netting has uneven and project- 30 ing sides and ends to dove-tail in and be firmly held by the body of the tie. The box is then filled with concrete within one-half inch ($\frac{1}{2}$ ") of the top and the said body of the cross tie has strips or rolls of wire netting D, 35 extending from end to end of the box for the purpose of reinforcing the central portion of the cross tie. The wire netting which heretofore has extended above the sides of the box or mold is then bent over the concrete 40 and is suitably fastened along the edges, after which the mold is filled to the top with concrete along the major portion thereof. In order to provide for the anchoring devices of the cross tie, two or more projections are 45 formed by adding concrete material to the top of the cross tie at the points desired, it being understood that the top of the cross tie while under construction is in reality the bottom of the tie when in use and hence the projection so formed would be on the base of the tie after it is removed from the mold.

In constructing a cross tie similar to that shown in Fig. 2, the cross tie E, is provided with three projections e, on the base which 50 are formed in the manner heretofore stated and, in this form, instead of employing two cushions registering with the rails, I may 55 employ a plank F, embedded in the upper

surface of the cross tie and resting on the wire netting G, which is also embedded in the concrete forming the cross tie. In this form, the strips of wire netting or the rolls extend from end to end and reinforce the structure.

In the device shown in Fig. 1, the rails are secured in place by means of the spikes H, but in the form shown in Fig. 2, I employ U-shaped bolts having the looped end thereof engaging with the plates I, embedded in the concrete, the said plates I having apertures 75 for the reception of the shanks of the bolts which shanks extend through apertures of the cross tie and cushion and projection a suitable distance to receive the clamping plates which engage the base of the rail, the 80 said clamping plates being secured in place through the medium of nuts run on the screw threaded ends of the bolt.

If desired, clamps J, may be substituted for the U-shaped bolts, the ends of the said 85 clamps being applied to the plates and to the cross tie and cushion in exactly the same relation as the bolts are applied in Fig. 2. By employing the clamp J, the clamping plates of Fig. 2, are done away with and the ends of 90 the clamp are bent to overlie and engage the base of the rail so that said rail is held firmly in position.

A further modification of the retaining device is shown as comprising a plate K, having 95 threaded apertures. The plate K, is embedded in the cross tie at the point that the plate I, is placed in Fig. 2, and the bolts l, are extended through the apertures of the cushion and tie and are threaded into the 100 plate K. The bolts thus employed are also run through the clamping plates which engage the ties of the rail and therefore said rail is held in position. It will be apparent that the substitution of the plate K for the 105 plate I, can readily take place without departing from the scope of the invention as the fastening means are analogous and would fall within the scope of the claims.

Having fully described my invention what 110 I claim as new and desire to secure by Letters Patent, is—

In a cross tie, a concrete or plastic body, a reinforce extending under the bottom along the sides and over the top of said body, a 115 cushion comprising alternate layers of netting and yielding fiber embedded in the concrete for supporting the rails.

In testimony whereof I affix my signature in the presence of two witnesses, this 21 day 120 of February, 1907.

JOHN S. SCHAEFFER.
